Primary Examiner—Raphael Barkai

Assistant Examiner—Randall H Gholson

(57) **CLAIM**

The ornamental design for a gas valve wrench, as shown and described.

DESCRIPTION

FIG. 1 is a perspective view of a gas valve wrench showing my new design; and,

FIG. 2 is a top view of the gas valve wrench, with the bottom view being identical.

1 Claim, 1 Drawing Sheet

FIG.1

FIG.2
